UNITED STATES PATENT OFFICE.

ANDREW P. RIEDELE, OF ST. CLOUD, MINNESOTA.

IGNITION SYSTEM FOR INTERNAL-COMBUSTION ENGINES.

1,370,670.

Specification of Letters Patent. Patented Mar. 8, 1921.

Application filed July 29, 1919. Serial No. 314,039.

To all whom it may concern:

Be it known that I, ANDREW P. RIEDELE, a citizen of the United States, and a resident of St. Cloud, in the county of Stearns and State of Minnesota, have made certain new and useful Improvements in Ignition Systems for Internal-Combustion Engines, of which the following is a specification.

My invention relates to ignition systems for internal combustion engines, and particularly to a device for indicating whether or not the several spark plugs of an engine are sparking properly.

It is a purpose of my invention to provide an indicating device of the above character which can be placed on the instrument board of an automobile to indicate any defects in the sparking of each and all spark plugs of an engine, such device being of simple construction and capable of application to any standard ignition system without necessitating radical changes therein.

I will describe one form of ignition system and one form of indicating device embodying my invention and will then point out the novel features thereof in claims.

In the accompanying drawings:

Fig. 1 is a diagrammatic view showing a portion of a conventional form of ignition system having applied thereto one form of indicating device embodying my invention.

Fig. 2 is a view showing in front elevation the indicating device shown diagrammatically in Fig. 1, applied to an instrument board of an automobile.

Fig. 3 is a vertical sectional view taken on the line 3—3 of Fig. 2.

Fig. 4 is a view showing in front elevation the main body of the indicating device removed from its casing.

Similar reference characters refer to similar parts in each of the several views.

Referring specifically to the drawings, the indicating device which forms the subject-matter of my invention is designated generally at D and as shown in Figs. 3 and 4, comprises a body plate B formed of suitable insulating material which is slotted at spaced intervals on its front side to provide channels C which are adapted to receive the ends or terminals k and k' of two sets of conductors K and K'. The terminals k and k' of each set of conductors are inserted into the channels C through openings P and P', respectively, each opening having a bottom wall 15 intermediate its ends to divide the

same into a rear compartment on the rear side of the body B to receive a conductor K or K' and the insulating material M with which it is covered, and a front compartment on the front side of the body for receiving a quantity of solder L for securing the end k or k' within the channel C and the opening P. As shown in Fig. 3, the wall 15 is formed with an opening to snugly receive the terminals k or k' of the conductors so that the solder when being poured into the front compartment cannot pass into the corresponding rear compartment and burn the insulation M on the conductors. The openings P and P' are of circular formation with the front compartment intersected by the channel C at a point centrally thereof, so that in effect the walls of the channels are provided at opposite points with semi-circular recesses. As shown in Fig. 4, the openings P are arranged in spaced relation to the opening P' and the openings of each set are disposed in longitudinal alinement.

When applying the conductor terminals k and k' to the body B they are inserted through the openings P and P' respectively until the required length projects beyond the front side of the body B whereupon they are bent at right angles and seated within the channels C. It will be noted that the terminals k of conductors K are bent in a direction opposite from the terminals k' of the conductors K', so that the terminals k and k' of each channel C are arranged in opposed relation with their confronting ends spaced to provide a spark gap G. After the terminals k and k' have been properly adjusted to secure a gap G of the desired length, they are securely fixed in such adjusted position by dropping pieces of molten solder L into the front compartment of the openings P and P'. When the solder L hardens the conductors K and K' are locked within the body B against accidental or intentional displacement, and with the terminals in angular formation such solder adheres to the conductors at the point of bending. In Figs. 2 and 3 I have shown the body B disposed within a recess formed in an instrument board E, the conductors K and K' extending through suitable apertures formed in the bottom wall of the recesses. The body B is held within the board E by a ring R which surrounds the body and projects from the board, as shown.

Permanently secured to the projecting portion of the ring R is a collar T, which is detachably secured to the board E by fastening members F. Interposed between the collar T and the body B is a disk H formed of insulating material and provided with openings O at points corresponding to the gaps G, so that when a spark occurs in any of the gaps it can be readily observed by the operator of the automobile. Above the openings O the plate H is provided with numbers which correspond to the number of cylinders comprised in an engine, so that the condition of the spark plug of a particular cylinder may be readily determined.

Referring now to Fig. 1, I have here shown only those parts of an ignition system which are necessary to a clear understanding of my invention, and in which 20 designates a distributor having stationary contacts 21, which are adapted to be successively closed by a rotating contact 22 fixed on a shaft 23. The contact 22 is connected to the high tension terminal of a 25 magneto (not shown) and therefore supplies current to the contacts 21 which form the terminals of a plurality of circuits, one side of which includes spark plugs S and the conductors K and K'. The other side of 30 these circuits are grounded through the engine in the usual manner. The indicating device D is here shown embodied in the circuits of the spark plugs S, the terminals k and k' forming a gap G and a circuit for 35 each spark plug S, so that as long as the condition of each circuit remains normal to secure the proper sparking at the plug, the spark will occur in the gap G. However, should any plug for any reason fail to spark 40 properly so that its corresponding circuit is disrupted, a spark fails to occur in the gap G, thus indicating the faulty condition of the plug or circuit. It will thus be seen that by interposing my indicating device in 45 the circuits of an ignition system, a visual

indication of the condition of each spark plug is given at all times. It will be understood that the conductors K and K' constitute the usual means in a conventional form of ignition system for supplying current to 50 the several spark plugs, only that such conductors are ordinarily continuous and are not provided with the gaps G to effect the visual indications. Such an arrangement obviously permits the application of my device to an ignition system of this character 55 without making any radical changes therein, so that the device may be applied to an automobile at a minimum cost.

Although I have herein shown and described only one form of ignition system and one form of indicating device embodying my invention it is to be understood that various changes and modifications may be made herein without departing from the 60 spirit of the invention, and the spirit and scope of the appended claims.

Having described my invention, what I claim is:-

1. An indicating device for ignition systems, comprising a body formed of insulating material, channels formed in the body, and openings communicating with the channels, and conductors extending through the openings and lying within said channels, 70 the conductors of each channel being arranged in spaced relation to each other to provide spark gaps.

2. An indicating device for ignition systems, comprising a body slotted upon one 80 of its faces to provide channels, and formed of openings which intersect the channels, conductors extending through said openings and lying within said channels, the conductors of each channel being arranged 85 in spaced relation to provide a spark gap, and molten metal adapted to be poured into said openings for securing the conductors within said channels.

ANDREW P. RIEDELE.
